OTTO GROTH, OF ROCHESTER, NEW YORK, ASSIGNEE TO EASTMAN KODAK COMPANY, OF ROCHESTER, NEW YORK, A CORPORATION OF NEW YORK.

FEEDING AND SUBMERGING DEVICE.

1,302,468.

Specification of Letters Patent. Patented Apr. 29, 1919.

Application filed July 16, 1917. Serial No. 180,868.

To all whom it may concern:

Be it known that I, OTTO GROTH, a citizen of the United States of America, residing in Rochester, in the county of Monroe 5 and State of New York, have invented certain new and useful Improvements in Feeding and Submerging Devices; and I do hereby declare the following to be a full, clear, and exact description of the same, reference 10 being had to the accompanying drawings, forming a part of this specification, and to the reference characters marked thereon.

This invention relates to nitrating machines, and more particularly to mechanism 15 for feeding and submerging material in the nitrating bath.

The objects of my invention are to provide, simple, reliable, and durable mechanism; to reduce the manual labor required. 20 and consequently the number of attendants; to avoid splashing of the acid; to materially reduce the volume of evolved nitric oxide fumes; to not only submerge the materials to be nitrated, such as cotton, below the 25 surface of the acid, but to break up lumps of cotton which may tend to form and to re-submerge any masses of wet cotton that tend to rise above the acid; to provide an immersing device having an endless surface which 30 is yieldingly mounted and partially submerged in the acid and is impositively driven so as to travel in the same general direction as the flow of acid and cotton, and to provide smooth continuous ribs upon the 35 submerging device which will be self clearing to substantially prevent masses of cotton adhering thereto. Other objects will herein-after appear.

In the accompanying drawing in which 40 like reference characters indicate the same parts throughout the several views:

Figure 1 is a side elevation of a nitrating machine embodying my invention, parts of the casing and drum of the centrifugal and 45 parts of the immersing device being broken away to more clearly show the internal structure.

Fig. 2 is a plan view of the apparatus.

Fig. 3 is a perspective view of the detached submerging device.

Fig. 4 is a perspective view showing the submerging device swung out of the nitrating chamber and into a draining chamber.

Fig. 5 is a diagrammatic sectional view

through the submerging roller taken perpendicularly to the axis of the submerging roller.

Fig. 6 is a corresponding diagrammatic sectional view taken at right angles to Fig. 5, the submerging roller being shown in side elevation.

In nitrating such material as cotton, concentrated sulfuric and nitric acids are brought into contact with the cotton in machines which circulate the acid usually in an endless path, the commonest of these machines being centrifugals. I have, therefore, illustrated my invention as embodied in such an apparatus. Part of the outer casing of the centrifugal of a conventional type is represented at 1. It is provided at its top with a peripheral flange 2, upon which rests a cover 3 provided at the rear with a gas-vent 4, and at its front part with a door 5. Within the centrifugal is a rotary drum 6 having a central tapering cone or hub 7 perforated in the conventional way (not shown). Upon the hub 7 is affixed a driving ring 8 more fully referred to hereinafter.

Upon opposite sides of the centrifugal, I provide at 21, 22 upwardly extending sleeves into which fit pins 19, 20, which are connected by hinges 17 and 18 to a torsionally flexible bar 16. Adjustably attached to this bar, by slot and bolt connections 14, 15, are the connected supports 12 and 13, the former carrying two vertical bearing arms 11 in which turns the shaft 10 of the feeding and immersing roll 9. This roll is provided with smooth, annular, coaxial, spaced flanges 23, 24, 25, and 26. The roll itself is preferably hollow, to enable it to cooperate properly with the dense acid and to keep the parts sufficiently light for easy manipulation. The dimensions of the parts are such that the roll is normally partly submerged beneath the surface of the acid, as indicated in Figs. 1, 5, and 6. It is yieldingly retained in its lower position by spring 30 on the end of support 12, said spring 30 having a hook 31 at its lower end engaging detachably over flange 2 of the casing 1. Sleeve 21 is provided with a thumb screw 32 for engaging the pin 19. The pin 20 is freely rotatable in the sleeve 22, although a thumb screw similar to 32 may be used in sleeve 22 if desired. Mounted

35 40 45 50 55 60 65 70 75 80 85 90 95 100 105

upon the arms 11 are side guides or deflectors 33, and upon the support 12 is a top guide 34.

The several parts of the submerging device and its supports are ordinarily made of steel which I find to be sufficiently durable in practice. For the parts which come in contact with the acid most frequently, any preferred acid resisting material such as aluminum could be substituted if necessary.

At one side of the centrifugal, and in rear of the sleeve 22, I attach a box 27 for the reception of the submerging roll 9 and its associated parts. This box is provided with a cover 28 and cut away seats 29 to receive the bar 16. During the interval when the submerging device is not in use it is kept in this covered receptacle to protect the operator from contact with the acid-soaked parts and to support it in the best position for draining. To remove the submerging device from the centrifugal to the box, the operator loosens thumb screw 32 and lifts pin 19 out of sleeve 21. He thereupon rotates bar 16 upwardly about hinge 18 until it is near enough to the vertical to be easily manipulated. It is then twisted by turning pin 20 in sleeve 22 and finally lowered by turning about hinge 18 until it rests in seats 29.

30 The flange 23 of the roll 9 is arranged to contact near its outer edge with the rotating ring 8 on hub 7, being resiliently pressed thereagainst by the spring 30, the bar 16 being sufficiently yielding under torsional stresses to permit of this limited rotary movement.

In use the centrifugal is filled with acid to the proper level and the drum 6 with its hub 7 is rotated at a relatively low speed, 40 thus moving the acid A in a circular or endless path past the feeding and submerging station constituted by roll 9 and its associated parts. Since this roll 9 is partially submerged, the stream of acid flowing 45 against its lower portion tends to turn it in the direction indicated by the arrows in Fig. 5. The friction between the rotating ring 8 and flange 23 also tends to move the roll in this same direction. It will thus be seen that the cylindrical or endless face of the roll 9, including the faces of the ribs 23, 24, 25, and 26, is driven frictionally and 50 positively so that its active submerging portion travels in the same general direction as the flow of material in the centrifugal.

It has been customary in this art for two men to attend to each centrifugal, one for feeding the cotton and the other for submerging it with an iron bar. My machine 60 merely calls for one attendant. This attendant merely drops the cotton C to be nitrated upon the moving surface of the concentrated acid A (Figs. 5 and 6), so that it will be carried into contact with the rotating roll 9 and ribs 23, 24, 25, and 26. These

elements engage and travel with the cotton, moving it progressively downward and forward beneath the acid and thoroughly incorporating it in the latter. Should any lumps of cotton tend to form, the rib structure will break them up or separate them into smaller clumps, the action being roughly similar to that of a harrow. Since the ribs are continuous and smooth, there is very little tendency for clumps of wet cotton to stick to them and be carried upwardly into the air where splashing and fuming would result; thus the smooth ribs coöperating with the stream of acid are practically self clearing. The guides 33 and 34 aid in bringing the cotton under the influence of the submerging roll and guide 34 tends to prevent any acid or wet clumps of cotton from being thrown or splashed upwardly by the roll, although, as just stated, the chance of wet cotton adhering to the roll is very slight indeed.

I find in practice that the resilient or yielding mounting for the submerging roll is important, as it permits the latter to function properly in spite of variations in the level of the acid, and in spite of the varying buoyancy of different sized batches of cotton that are fed into the machine. Thus with the larger batches of cotton, the roll will ride upwardly upon them and force them under the acid. Furthermore, this yielding construction permits clumps of cotton to pass between the ring 8 and flange 23 without any injury to the mechanism.

Cotton which has been submerged in acid sometimes tends to float or become partially raised above the surface of the acid in such a way as to cause a large amount of fuming or evolution of nitric acid fumes, which are injurious to the attendants and represent a waste of acid. My device greatly reduces this trouble, because any clump of cotton which rises above the surface is immediately and repeatedly swept under the roll 9, where it is again submerged.

Having thus described my invention, what I claim and desire to secure by Letters Patent of the United States, is:

1. In nitrating apparatus, means for circulating the acid in a defined path, and a separate feeding and immersing member having a moving endless feeding and submerging face, part of which is arranged below the level of the acid, the active submerging portion of said face moving in the same general direction as the circulating acid.

2. In nitrating apparatus, means for circulating the acid in a defined path, a feeding and immersing member mounted transversely to said path and having an endless feeding and submerging face, part of which is below the level of the acid and moves in the same general direction as the circulating acid.

- acid, and means for yieldingly supporting said member.
3. In nitrating apparatus, means for circulating the acid in a defined path, a separate feeding and immersing member mounted transversely to the path of the acid and having an endless feeding and submerging face, part of which is arranged below the level of the circulating acid, said face being 10 provided with spaced ribs and being composed of acid resisting material.
4. The combination set forth in claim 3, the ribs being smooth and continuous.
5. In nitrating apparatus, means for circulating the acid in a defined path and a separate partially submerged feeding and submerging cylinder mounted to rotate about 15 an axis transverse to said path.
6. In combination, the elements defined 20 in claim 5, said cylinder being provided with spaced, smooth, continuous ribs.
7. In combination, the elements defined in claim 5, the cylinder being provided with smooth, continuous, spaced, coaxial, annular 25 ribs.
8. In nitrating apparatus, a centrifugal having a central rotating hub, and a feeding and submerging member frictionally driven from said hub.
- 30 9. In nitrating apparatus, a centrifugal having a rotating hub therein provided with a driving ring, and a feeding and submerging member driven frictionally from said ring.
- 35 10. In nitrating apparatus, a centrifugal provided with a rotary hub carrying a driving ring, and a feeding and submerging roll provided with annular flanges, one of the flanges frictionally engaging said ring to 40 be driven thereby.
11. In nitrating apparatus, means for circulating the acid in a defined path, a separate feeding and submerging cylinder arranged transversely of the path, and guides 45 for directing the fibers to said cylinder.
12. In nitrating apparatus, means for circulating the acid in a defined path, a feeding and submerging cylinder arranged transversely of said path and provided with 50 spaced annular ribs, and guides for directing the fiber to said cylinder and ribs.
- 55 13. In a feeding and submerging device, a bar provided with a lateral bearing support, and a feeding and submerging roll carried by said support.
14. In a feeding and submerging device, a bar, a lateral bearing support adjustably mounted on said bar, and a feeding and submerging roll carried by said support.
- 60 15. In apparatus for feeding and submerging material into a body of liquid, a feeding and submerging station and means for moving the liquid past said station, said
- station including a feeding and submerging roll mounted upon a support, said support 65 being attached at one end to a yieldable member and at the other end to a downwardly pulling element.
16. In apparatus for feeding and submerging material into a body of liquid, a 70 feeding and submerging station, means for moving the liquid past said station, a rotary driving member at said station, said station including a feeding and submerging roll mounted upon a support, said support being 75 rotatably mounted at one end and attached at the other end to a spring for rotating said support downwardly and pressing said roll into contact with said rotary driving member. 80
17. In nitrating apparatus, a nitrating chamber, a draining chamber, a frame carrying a feeding and submerging device, said frame being mounted to swing from said nitrating chamber to said draining chamber. 85
18. In nitrating apparatus, a nitrating chamber, a draining chamber, a frame carrying a feeding and submerging device, said frame being pivotally mounted at one end to swing about horizontal and vertical axes 90 from said nitrating chamber to said draining chamber, there being adjacent the nitrating chamber a detachable support for the other end of said frame.
19. In nitrating apparatus, a nitrating 95 chamber, a draining chamber, a frame carrying a feeding and submerging device, said frame being mounted to swing from said nitrating chamber to said draining chamber, said draining chamber being provided with 100 a cover and seats for the frame which permit the cover to be closed when said frame and device are in the draining chamber.
20. In apparatus for feeding and submerging material into a body of liquid, a 105 feeding and submerging station, means for moving the liquid past said station, said station including a rotary feeding and submerging device in driven contact with said moving liquid. 110
21. In apparatus for feeding and submerging material into a body of liquid, a feeding and submerging station, means for moving the liquid past said station, a driving element adjacent said station, and a rotary feeding and submerging device 115 impositively driven from said moving liquid and from said driving member. 115
- In testimony whereof, I have signed this specification in the presence of two witnesses 120 this 5th day of July 1917, at Rochester, N.Y.
